SIGNORS TO NATIONAL SAFETY APPLIANCE COMPANY, OF SAN FRANCISCO, CALI-
FORNIA, A CORPORATION OF CALIFORNIA.

ELECTROPNEUMATIC VALVE.

1,392,544.

Specification of Letters Patent.

Patented Oct. 4, 1921.

Application filed March 19, 1918. Serial No. 223,301.

To all whom it may concern:

Be it known that we, EUGENE WIET and FOREE CHITTENDEN, citizens of the United States, residing at the city and county of San Francisco and State of California, have invented certain new and useful Improvements in Electropneumatic Valves, of which the following is a specification.

The present invention relates to an electrically controlled valve mechanism particularly designed for operation against a fluid pressure and unseated thereby, the valve being manually moved to closed position and normally maintained in such position by suitable magnetic means.

The improved construction is designed particularly for use in signal apparatus, preferably of the whistle or audible type, said signal being sounded while the valve is in open position and until such time as the valve member is manually moved to cut off the flow of fluid supply for operating such signal at which time the electromagnetic means retains the valve in closed position.

With the above mentioned and other objects in view, the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

To more fully comprehend the invention, reference should be had to the accompanying sheet of drawings, wherein—

Figure 1 is a view of the preferred embodiment of the invention, illustrating the valve plunger in open position, and disclosing the controlling circuit for energizing the magnet coil.

Fig. 2 is a sectional view taken on line 2—2 of Fig. 1, illustrating more fully the construction of the valve chamber.

Referring more particularly to the drawings, 1 indicates a suitable tubular valve chamber provided with a laterally disposed outlet 2 to which is connected in any suitable manner, as by an elbow 3, a whistle or other fluid operated signal 4 of the audible type. To the lower end of the casing 1 is

connected, by suitable couplings 5, a fluid supply connection 6, the flow of fluid, under pressure therefrom into the casing 1 being controlled by a service cock 7.

Longitudinally movable within the upper end of the valve casing 1 is a valve plunger 8, having sufficient movement in said casing to extend at its lower or free end below the lateral opening 2 and cut off the flow of fluid through said opening.

To the upper end of said valve plunger 8 extending exteriorly of said casing is attached through a flexible joint 9, preferably of the ball type, an operating stem 10 movable in guide brackets 11 extending laterally from a guide standard 12, the lower end 13 of which is attached to and is supported by the valve casing 1. The upper end of the stem 10 is provided with a hand engaging portion 14.

Extending parallel with the guide casing 1 and disposed one on either side thereof, are the magnet coils 15 connected by a yoke 16, the ends of said coils being connected in circuit with a battery 17, said circuit being provided with a controlling switch 18 which when closed completes a circuit from the battery 17 to the magnet coils 15, energizing said coils.

An armature 19 is carried by the stem 10 and the same is adapted on the downward manual movement of the stem 10 to be forced into contact with the energized coils 15 and be retained in said position during such time as the plunger 8 is depressed to cut off the flow of fluid through the lateral opening 2, and thus preclude the operation of the signal 4.

On the interruption of the current from the battery 17 to the coils 15, as by the opening of the switch 18, the coils will be de-energized and the fluid pressure against the lower flat face 20 of the plunger 8 will force said plunger upwardly and open the lateral outlet 2, at which time fluid under pressure will be permitted to pass therethrough and operate the signal 4.

The upward movement of the armature 19 is such as to create a sufficient gap between the armature and the coils 15 to prevent the drawing of the armature into contact with the coils on the closing of the switch 18; thus the signal will be sounded until such time as the stem 10 is manually

depressed against the fluid under pressure to force the armature in contact with the coils 15.

Having thus described our invention, what we claim as new and desire to protect by Letters Patent is:—

In combination with a valve casing of substantially T formation provided with an open ended bore having parallel side walls 10 and formed intermediate of its length with a lateral outlet communicating with said bore, a valve controlled pipe connected to the lower end of said bore for supplying fluid under pressure to said bore, a longitudinally movable valve having parallel side walls received at one end in the upper end of said bore, said valve being of a diameter to have a sliding fit within the bore with the walls of said bore and capable of movement 15 therein against fluid pressure in said bore to extend below said fluid outlet to close the same, the outer end of said valve being

formed with a ball end, a frame extending parallel with said casing and provided on its upper portion with laterally extended 25 ported guide arms overlying the upper open end of said bore, a longitudinally movable operating stem extended through said ported arms in alignment with said valve and provided at its lower end with a socket for engaging said ball to provide a flexible connection between said valve and stem, and electrically operated releasable means associated with said stem for retaining the same in closed position at one end of its longitudinal 30 movement in one direction.

In testimony whereof we have signed our names to this specification in the presence of two subscribing witnesses.

EUGENE WIET.
FOREE CHITTENDEN.
